UNITED STATES PATENT OFFICE.

JOHN E. LAING, OF KANSAS CITY, MISSOURI.

COMB.

1,108,375.

Specification of Letters Patent. Patented Aug. 25, 1914.

Application filed November 3, 1913. Serial No. 798,947.

To all whom it may concern:

Be it known that I, JOHN E. LAING, a citizen of the United States, residing at Kansas City, in the county of Jackson and State of Missouri, have invented certain new and useful Improvements in Combs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to combs, and more particularly to metallic combs, the principal object of the invention being to provide a comb having a heat conducting body whereby waves or curls may be removed from the hair and the hair be made to lie straight and smooth. In accomplishing this object I have provided improved details of structure hereinafter described and illustrated in the accompanying drawings wherein:

Figure I is a perspective view of a comb constructed in accordance with my invention. Fig. II is a central longitudinal section of the same. Fig. III is a transverse sectional view of the comb.

Referring more in detail to the parts:—
1 designates the comb which comprises a heavy rectangular back 2 and integral tines 3 having straight forward edges 4, inclined back portions 5, and slightly rounded points 6. Near the center of each end of the back 2, are threaded apertures 7 in which is removably mounted a long metal shank 8 having a non-heat conducting handle 9 at its outer extremity. The comb is preferably formed from a solid piece of metal, which is slotted at regular intervals along its acute edge to form the tines.

In using the device, supposing a person has had their hair dressed in a manner which leaves the strands full of waves or curls that resist any effort to make them lie smooth and straight, the comb is placed over a burner (not shown) and heated to a certain temperature, in which condition it is drawn

through the hair, so that rounded points 6 touch the scalp and the hair moves between the tines in a line almost parallel to the inclined edges 5. In this manner the strands of hair are subjected to heat from between the long parallel surfaces of the tines and are made to lie straight and smooth. By providing a threaded aperture at each end of the body, the handle may be applied to either end and thereby change the position of the comb relative to the head. For example if the comb is used in the right hand the air from the center of the head may be combed forward and the inclined edges 5 follow close to the head, but if it is desired to comb the hair at the back of the head, the handle must be reversed in order to bring the comb in the same relative position with the head.

The comb is particularly useful in drying the hair after a shampoo because the heat is applied more directly to the strands leaving them straight and smooth.

It is apparent that by providing the long handle the comb may be conveniently used without burning the hands, and that by slightly rounding the points of the tines the comb cannot injure the scalp.

Having thus described my invention, what I claim as new therein and desire to secure by Letters Patent, is:

1. A comb comprising a body member having relatively wide and narrow opposite longitudinal faces, and slit transversely to form spaced tines with the slots extended into the body at the narrow free edge to form channels of graduated depth.

2. A comb comprising a heat retaining back having end apertures, a plurality of heat conducting tines integral with said back, and a handle adapted for insertion into either of said apertures.

3. A comb comprising a heat retaining body, a handle adapted for application to either end of said body, and a plurality of tines integral with said body having straight forward edges, inclined rear edges and slightly rounded points.

4. A comb comprising a heat retaining

body, a non-heat conducting handle adapted for application to either end of said body, and a plurality of heat conducting tines integral with said body having straight forward edges and inclined rear edges.

5. A comb comprising a heat retaining body, having a plurality of equally spaced elongated channels along one side adapted to receive heat from said body, and a handle

adapted for application to either end of said body.

In testimony whereof I affix my signature in presence of two witnesses.

JOHN E. LAING.

Witnesses:

ARTHUR W. CAPS,
L. E. COATS.
